UNITED STATES PATENT OFFICE.

RICHARD R. MOFFATT, OF BROOKLYN, NEW YORK, ASSIGNOR TO
IMPERIAL ORE SEPARATOR COMPANY, A CORPORATION OF
NEW YORK.

MAGNETIC ORE-SEPARATOR.

No. 825,672.

Specification of Letters Patent.

Patented July 10, 1906.

Application filed July 19, 1904. Serial No. 217,222.

To all whom it may concern:

Be it known that I, RICHARD R. MOFFATT, a citizen of the United States of America, and a resident of Brooklyn, county of Kings, and 5 State of New York, have invented certain new and useful Improvements in Magnetic Ore-Separators, of which the following is a specification.

My invention relates generally to magnetic ore-separators, and more especially to an apparatus for separating ore containing feebly-magnetic particles.

The object of my invention is the production of an apparatus in which a very powerful field or fields can be created and in which at the same time two or more fields of varying intensity may be produced, so that the strongly-magnetic particles are separated at one point, while the feebly-magnetic particles 20 are separated at a subsequent point.

To this end the invention comprises the features of construction and combinations of parts, as will more fully hereinafter appear.

In the drawings, Figure 1 is an end view of 25 an apparatus embodying my invention and shown partly in section. Fig. 2 is a longitudinal sectional view of Fig. 1, taken on an irregular line. Fig. 3 is a side elevation. Figs. 4, 5, 6, and 7 show various forms of 30 detachable shoes for the poles.

Similar characters of reference indicate corresponding parts in the different views.

A structure capable of concentrating magnetic lines of force so as to produce a field or 35 fields of great intensity is obtained by means of a magnet consisting of the upper and lower poles 7 and 8, of which there are only two in the present instance, energized by the coils 3 and 4 and secured to and in circuit with the 40 end frames 1 by means of the cores 2. The upper core is adjustably secured to the end frames by means of the longitudinal bolts 5 and vertical bolts 6, by means of which the upper pole can be adjusted with relation to 45 the lower one.

The end frames are provided with apertures 11 of a sufficient size to enable the feed-conveyer 12 to pass horizontally through the 50 interpolar space. This feed-conveyer moves rectilinearly and is in the present instance in the form of an endless belt passing over the

drums 13, the material being fed to the said conveyer by means of the hopper 14 or otherwise. Intersecting this feed-conveyer in the interpolar space is a separating-conveyer 15, 55 also in the form of an endless belt, passing over the drums 16, suitably mounted on the shafts 17, carried by the brackets 18, mounted in the framework of the machine. On top of the upper pole there is a suitable idler 19, 60 over which the endless conveyer passes.

Means are provided whereby two fields of varying intensity will be produced between the upper and lower poles of the magnet. As there is in the present instance only one 65 upper and one lower pole and one separating-conveyer, there will be produced two fields of force of varying intensity at different points of the same separating-conveyer or at different points in the same interpolar space. In 70 this manner the strongly-magnetic particles will be separated at one point, while the feebly-magnetic particles will be separated at a succeeding point. Preferably this is accomplished by abruptly intensifying the lines of 75 force in the interpolar space, so that they are greater at one point of the intersection than at a preceding point. This abrupt increasing in the intensity of the magnetic flux in the interpolar space is preferably caused by 80 bringing the feed-conveyer abruptly in closer proximity to the upper pole. Various means can be used for accomplishing this. Preferably I provide a deflecting attachment 20, consisting of the frame 21, mounted on the 85 lower pole and carrying two rollers 22 and 23 disposed in such a manner that a portion of the feed-conveyer is brought abruptly nearer to the upper pole than the preceding portion of the said feed-conveyer. When the ore reaches the roller 22, it will pass underneath the same and onto that portion of the conveyer designated by the reference-letter 24, where the highly-magnetic particles will be 90 attracted to the separating-belt. The remaining portion of the ore will pass on until it reaches that portion of the conveyer designated by 25, where the more feebly-magnetic particles will be attracted to the separating-conveyer and conveyed out of the machine. 100 The movement of the particles out of the machine is facilitated by the extension 26 on the

upper pole which projects beyond the field of force proper and in the direction of the movement of the separating-conveyer.

The deflector for the feed-conveyer is adjustable by means of the slot 27 and screw 28, whereby the distance of the feed-conveyer with relation to the upper pole can be varied. Instead of this or in addition thereto I may provide one or both poles with removable shoes 9 and 10 in order to intensify the magnetic lines of force abruptly at a certain point of the intersection of the two conveyers. In Figs. 4, 5, 6, and 7 I have shown various forms of shoes. The shoe shown on the lower pole in Fig. 2 is provided with step-like faces abruptly decreasing the distance between the upper and lower poles, thereby intensifying the lines of force.

What is claimed is—

1. In a magnetic ore-separator, the combination of upper and lower poles of opposite polarity, rectilinearly-moving feed and separating conveyers intersecting each other in the interpolar space and means whereby the feed-conveyer is abruptly brought into closer proximity to the upper pole at one point than at the preceding point, whereby the strongly-magnetic particles are separated at one point of the separating-conveyer and the feebly-magnetic particles are separated at another point on the same separating-conveyer.

2. In a magnetic ore-separator, the combination of upper and lower poles of opposite polarity, rectilinearly-moving feed and separating conveyers intersecting each other in the interpolar space and adjustable means whereby the feed-conveyer is abruptly brought into closer proximity to the upper pole at one point than at a preceding point, whereby the strongly-magnetic particles are separated at one point on the separating-conveyer and the feebly-magnetic particles are separated at another point on the same separating-conveyer.

3. In a magnetic ore-separator, the combination with intersecting feed and separating conveyers, of a magnet having upper and lower poles on opposite sides of the convey-

ers, all constructed and arranged so as to produce two fields of varying intensity between the said poles.

4. In a magnetic ore-separator, the combination with intersecting feed and separating conveyers, of a magnet having an upper pole and a lower pole of opposite polarity on the opposite sides of the conveyers, all constructed and arranged so as to produce two fields of varying intensity between the said poles.

5. In a magnetic ore-separator, the combination with intersecting feed and separating conveyers, of a magnet comprising end frames having apertures for the passage of one of said conveyers therethrough, and upper and lower poles in circuit with the end frames.

6. In a magnetic ore-separator, the combination with intersecting feed and separating conveyers, of a magnet comprising end frames having apertures for the passage of one of said conveyers therethrough, and upper and lower poles in circuit with the end frames forming two fields of force of varying intensity.

7. In a magnetic ore-separator, the combination with intersecting feed and separating conveyers, of a magnet comprising end frames having apertures for the passage of one of said conveyers therethrough, and an upper and a lower pole of opposite polarity forming two fields of force of varying intensity.

8. In a magnetic ore-separator, the combination with a magnet having upper and lower poles of opposite polarity, of feed and separating conveyers intersecting each other in the interpolar space, and step-like faces on one of said poles abruptly decreasing the distance between the said poles.

Signed at New York this 16th day of July, 1904.

RICHARD R. MOFFATT.
